US0D1111340S

(12) **United States Design Patent** (10) Patent No.: **US D1,111,340 S**
(45) Date of Patent: ** Feb. 10, 2026

(54) **SHOE**

(71) Applicant: **Hainan Bmai Sports Technology Co., Ltd.**, Chengmai (CN)

(72) Inventor: **Bo Huang**, Chengmai (CN)

(73) Assignee: **Hainan Bmai Sports Technology Co., Ltd.**, Chengmai (CN)

(**) Term: **15 Years**

(21) Appl. No.: **29/974,755**

(22) Filed: **Nov. 25, 2024**

(30) **Foreign Application Priority Data**

Jul. 29, 2024 (CN) 202430473957.2

(51) LOC (15) Cl. **02-04**

(52) U.S. Cl.

USPC **D2/908**; D2/907; D2/957

(58) **Field of Classification Search**

USPC D2/896, 902, 905, 906, 907, 908, 943, D2/944, 945, 946, 947, 951, 957, 959,

D2/960
